UNITED STATES PATENT OFFICE

110,393

DESIGN FOR A PLATFORM SCALE

Claude R. Kirk, River Forest, Ill.

Application April 7, 1938, Serial No. 76,357

Term of patent 14 years

To all whom it may concern:

Be it known that I, Claude R. Kirk, a citizen of the United States and a resident of River Forest, in the county of Cook and State of Illinois, have invented a new, original, and ornamental Design for a Platform Scale, of which the following is a specification, reference being had to the accompanying drawing, forming a part thereof, and in which the single figure is a perspective view of a platform scale showing my new design, the printed matter being merely illustrative.

I claim:

The ornamental design for a platform scale, as shown and described.

CLAUDE R. KIRK.
